UNITED STATES PATENT OFFICE

GRiffin S. ACKLEY, OF BUFFALO, NEW YORK.

BRAKE MECHANISM.

No. 910,688.

Specification of Letters Patent.

Patented Jan. 26, 1909.

Application filed May 28, 1908. Serial No. 435,482.

To all whom it may concern:

Be it known that I, GRIFFIN S. ACKLEY, a citizen of the United States, residing at Buffalo, in the county of Erie and State of New York, have invented a new and useful Improvement in Brake Mechanisms, of which the following is a specification.

This invention relates more particularly to that type of brake mechanisms for cars in which a hand-actuated brake staff, or crank shaft is geared to and rotates a chain drum having a spiral-like periphery so that the chain winds upon peripheral portions of successively decreasing radius, whereby the slack of the chain is quickly taken up and the leverage thereon increases as the rotation of the staff and drum is continued.

The winding mechanism, including the drum and gearing, and containing frame therefor, is ordinarily sold to the railroads for installation on cars already equipped with the brake staffs and other brake parts, and as different cars vary considerably in construction and the brake staffs are located in different positions thereon, a winding mechanism which is suitable for one car can only be applied to another car with much labor and considerable expense by a skilled mechanic. In these winding mechanisms as heretofore constructed, the brake staff constitutes the bearing shaft for one or more of the gears, and must be specially machined and fitted to the winding mechanism, which adds materially to the cost of installation, and usually requires the work to be done in a well equipped machine shop.

One object of this invention is to produce a practical and efficient chain winding mechanism of a construction which adapts it to be readily adjusted to cars which differ in construction or have the brake parts differently located thereon, and which also enables the brake staff to be fitted or connected to the winding mechanism with the minimum expense and labor.

Other objects of the invention are to improve the construction of these winding mechanisms so that the brakes can be set quickly with less exertion and so that they will release readily; also to provide a chain winding drum of novel construction which operates more quickly to take up the slack in the chain and give the maximum leverage thereon; also to provide simple but safe and reliable means for adjustably attaching the

chain to the drum, whereby the same drum can be used where a greater or less length of chain must be wound up to set the brakes.

In the accompanying drawings, consisting of two sheets: Figure 1 is a plan view, partly in section, of a brake mechanism embodying the invention, different portions of the same on the car being indicated by full and broken lines. Fig. 2 is a sectional elevation, on an enlarged scale, thereof. Fig. 3 is a bottom plan view thereof. Fig. 4 is a side elevation thereof. Fig. 5 is a sectional plan thereof in line 5—5, Fig. 4. Fig. 6 is a horizontal section of the drum, in line 6—6, Fig. 2. Fig. 7 is a similar view showing another chain adjustment. Fig. 8 is a fragmentary elevation of the drum partly in section in line 8—8, Fig. 7.

Like letters of reference refer to like parts in the several figures.

The containing or supporting frame of the winding mechanism *c* comprises a horizontal base or plate *A* which is securely fastened to the under side of the car floor *a*, preferably by bolts *a'* at the four corners of the base, and an adjustable yoke *B* of substantially U-shape which extends diagonally beneath the base and is rigidly secured at opposite ends to diagonally opposite corners thereof. In the construction shown, the yoke is secured to the base by two of the bolts *a'* for fastening the base to the car floor, and the base is provided with depending tongues *b*, Figs. 3 and 4, which engage in grooves in the ends of the yoke to cooperate with the bolts in holding the yoke rigidly in position. The yoke can be secured in the diagonal position shown by full lines in Figs. 2—5, or it can be secured in the other diagonal position indicated by broken lines in Fig. 3, it being secured in one or the other position, depending upon the position of the base on the car.

C represents the upright brake staff, which, as usual, has a hand crank at its upper end and is journaled at or near its upper end in a suitable bearing (not shown) on the car, and is provided near its lower end with a ratchet wheel *c'* for holding it when it is turned to apply the brake.

D represents a pinion which is secured to the lower end of the brake staff and meshes with gear teeth *e* on the chain drum *E* for rotating the latter to wind the brake chain *F* thereon. The base plate *A* is provided with an integral hollow bearing boss *d*, Fig. 2,

which preferably extends up into a hole in the car floor through which the brake staff passes, and the pinion D has an integral shaft or sleeve d' which extends into and is journaled in said bearing boss, in which it is retained by a suitable collar or the like d^2 . The pinion is thus journaled on the base plate A entirely independently of the brake staff and the latter is simply secured to the pinion for turning it. As shown, the lower end of the brake staff is square and is secured in a square socket or hole in the pinion shaft by a cotter pin d^3 , but the staff could be secured to the pinion in any other suitable way. With this construction it is only necessary for the lower end of the staff to be squared so as to enter the socket of the pinion, and as the pinion is journaled independently of the staff it will turn freely and not bind even if the staff does not fit perfectly in the pinion or is somewhat eccentric thereto. The pinion is also retained in its bearing independently of the staff by the collar d^2 and no harm could arise from the loss or breaking of the cotter pin d^3 , which, however, supplements the collar in retaining the pinion in its bearing.

A roller bearing d^4 of any suitable construction is preferably provided for the pinion shaft in the bearing boss d between the pinion and its retaining collar d^2 .

The chain drum E is journaled between the base A and yoke B. In so far as the other features of the mechanism are concerned, the drum could be of the spiral-form commonly used, but preferably the periphery thereof on which the chain winds is composed of a concentric helical portion e' of relatively large radius which extends part way around the drum, a concentric cylindrical portion e^2 of smaller radius, and a substantially straight inclined portion e^3 which connects the large and small portions e' and e^2 . A flange or rib e^4 encircling the drum prevents the chain from slipping from one to the other portion thereof. The large concentric portion e' of the drum is longer than a spiral portion of equal maximum radius extending the same number of degrees around the drum, and the straight portion e^3 , being the shortest path between the large and small concentric portions, increases the leverage on the chain more rapidly than a spiral portion could, so that with a drum of the described form the slack of the chain can be taken up and the maximum leverage thereon secured with a shorter rotary movement than with a spiral drum of the same maximum radius.

The chain F is provided with a long end link f which is curved on the same radius as the large concentric portion e' of the drum and is secured in a circumferential channel f' in the drum by bolts or pins f^2 passing through the link and through two holes f^3 in the drum, which enables different adjustments of the

chain and thus adapts the drum to be used with brakes in which different lengths of chain have to be wound on the drum to take up the slack. Each bolt f^2 shown has a head seated between ribs on the top of the drum 73 and is held in place by a cotter pin passing through holes in the ribs over the bolt head. This way of retaining the chain bolt is much more reliable than a nut or other securing device on the bolt which could work loose and allow the chain to be detached. The curved link f bears for its full length on the surface of the drum and does not exert any lateral strain on the bolts f^2 . The two bolts passing through the link afford a doubly safe connection, for if the forward bolt, which normally receives the strain, breaks the other bolt will hold the chain. When both bolts are used, as shown in Fig. 7, the chain will swing away from the drum at the rear end of 85 the end link f , whereas if the rear bolt f^2 is removed the end link can swing outwardly on the forward bolt, as indicated by dotted lines in Fig. 6, the connection thus enabling a less or greater length of slack chain to be 90 taken up before the leverage is increased. This attaching device is preferred but other means could be employed for attaching the chain to the drum, and the described adjustable connection for the chain could be 95 used with drums of other construction.

The drum is journaled on a stud axle G, Fig. 2, which is rigidly fixed at its upper end to the base A of the frame and fits loosely at its lower end in a hole in the yoke B. The 100 yoke thus braces the lower end of the axle but it can be readily detached from the base and removed to permit the drum to be slipped onto and off of the axle. A roller bearing H for the drum surrounds the upper 105 or fixed end of the axle G in a bore in the large end of the drum. This roller bearing does not extend into the small cylindrical end 110 e^2 of the drum, which enables this part of the drum to be made of smaller diameter than otherwise, thereby giving greater final leverage. The axle passing through the small end of the drum serves to steady it or hold it from being pulled out of the vertical position, but the rollers H on the rigid upper end of 115 the axle constitute the real bearing for the drum.

The described winding mechanism is more universally adaptable to different makes of cars than those heretofore made. The frame 120 can be secured on the car in different positions as may be required by reason of different arrangements of the car frame members and different locations of the brake staff, and the yoke B can be adjusted to whichever of 125 its positions will place it more nearly in the line of draft on the chain to prevent the drum from canting. Very little work is required to connect the staff to the pinion because, as explained, the staff does not form 130

the bearing for the pinion D and therefore does not have to be accurately fitted, as in constructions where it forms the pinion shaft and must be properly fitted to bearings in 5 the frame of the winding mechanism. As the pinion D has a firm bearing in the frame, no bearing is required for the lower end of the brake staff other than the socket in the pinion. The adjustable chain connection for 10 the drum permits the winding mechanism to be placed in different positions without lengthening or shortening the chain or to be used with chains requiring different lengths thereof to be wound up to set the brakes. 15 The roller bearing for the pinion D co-operates with that for the drum to make the mechanism operate easily and insures the ready releasing of the brakes which is not possible if the pinion does not rotate freely.

20 I claim as my invention:

1. In a brake mechanism, the combination of a winding drum, a frame on which the same is journaled comprising a base adapted to be secured to the car, and a brace for the 25 drum journal, and means for rigidly securing said brace in different relations to said base, substantially as set forth.

2. In a brake mechanism, the combination of a winding drum, a frame on which the 30 same is journaled comprising a base adapted to be secured to the car, and a yoke which extends from end to end of said base beneath the same and forms a bearing for the drum journal, and means for securing said yoke in 35 either of two different diagonal positions on the base, substantially as set forth.

3. In a brake mechanism, the combination of a winding drum, a frame on which the same is journaled comprising a base, and a 40 yoke which extends diagonally beneath the same and forms a bearing for the drum journal, and bolts at the four corners of said base for securing it to the car, said yoke being secured to said base by the bolts at diagonally 45 opposite corners of the base, substantially as set forth.

4. In a brake mechanism, the combination of a winding drum, a supporting frame for the same comprising a base adapted to be secured to the car and a yoke which is adjustable to different positions on said base, a stud axle for said drum rigidly secured to said base and bearing loosely in said yoke, and a roller

bearing between said drum and said stud axle, substantially as set forth. 55

5. In a brake mechanism, the combination of a winding drum, a frame on which said drum is journaled secured to the car, a pinion geared to said drum and having a hollow shaft, a bearing on said frame in which said hollow shaft is journaled, and a brake staff having an end portion which is secured in 60 said hollow shaft and is located within said bearing, substantially as set forth.

6. In a brake mechanism, the combination 65 of a winding drum, a frame on which said drum is journaled secured to the car and having an integral bearing boss for a pinion, a pinion geared to said drum and having an integral hollow shaft journaled in said bearing boss, and a brake staff having an end portion which extends through said hollow shaft, substantially as set forth.

7. In a brake mechanism, a chain drum having a periphery upon which the chain 75 winds, composed of a concentric helical portion of relatively large radius extending part way around the drum, a concentric portion of smaller radius, and a substantially straight portion connecting said large and small concentric portions, substantially as set forth. 80

8. In a brake mechanism, the combination of a chain drum having a peripheral channel intersected by a plurality of bolt holes, a chain having a curved link located in said 85 channel, and a bolt or pin adapted to be placed in one or the other of said bolt holes to adjustably secure said chain to said drum, substantially as set forth.

9. In a brake mechanism, the combination 90 of a chain drum, a chain, and a fastening bolt for said chain passing vertically through one of the chain links and through holes in the drum, said bolt having a head at its upper end seated between projecting parts on the 95 upper portion of the drum, and a retaining device for the bolt passing through said projecting parts on the drum above said bolt head, substantially as set forth.

Witness my hand, this 26th day of May, 100
1908.
